UNITED STATES PATENT OFFICE:

WILLIAM P. THOMSON, OF PHILADELPHIA, PENNSYLVANIA.

RAIL-JOINT.

No. 872,477.

Specification of Letters Patent.

Patented Dec. 3, 1907.

Application filed February 8, 1907. Serial No. 356,025.

To all whom it may concern:

Be it known that I, WILLIAM P. THOMSON, of Philadelphia, Philadelphia county, Pennsylvania, have invented a new and useful 5 Rail-Joint, of which the following is a full, clear, and exact description; reference being had to the accompanying drawings, forming part of this specification, in which—

Figures 1 to 12, inclusive, are side views of 10 different forms of rail joints embodying my invention and hereinafter more particularly described.

My invention has relation to rail joints, and is designed to provide a joint which is especially adapted for use under modern conditions, in which locomotives and cars of greatly increased weight cause an excessive loading of the tracks. It has been found that this excessive loading produces so great 20 a deflection in the tracks that the tendency of the rails to creep ahead of the load has been correspondingly increased; and, therefore, under these conditions, the joint creeps forward with the rails toward the tie in front of 25 the joint and away from the tie in the rear of the joint, unless spiked or otherwise fastened to both of these ties in the manner commonly practiced. The front of the joint is understood to mean the end in the direction 30 in which the load is moving, and the rear of the joint the end away from which the load is moving after it has passed the abutting ends of the rails. Therefore, in order to maintain a fixed spacing of the two 35 supporting ties with reference to the abutting ends of the rails, it has been the common practice to provide the front and rear portions of each of the splice bars with spike slots or other means for anchoring to the ties 40 to prevent the creeping of the joint forward over the ties. The further development of the art, however, has introduced various extensions of splice bars below the base of the rail which in any case may be given a bearing against all or a portion of the rear side of 45 the tie in advance of the abutting ends of the rails.

My invention relates to a splice bar unsymmetrically designed, in the manner hereinafter clearly set forth, so that a fixed spacing of the ties may be maintained without fastening this bar in any way to more than one of the supporting ties; but, at the same time that it is thus made practicable to 55 shorten the forward portion of the splice bar, the rear portion is made longer than the for-

ward portion so that spiking or other fastening facilities may be afforded for anchoring the splice bar to the rear tie. In this way the rear portion will draw the rear tie ahead 60 along to the same extent that the creeping rails carry the splice bar along with them.

It has been determined in practice that, when the creeping of the ties is pronounced, it is impracticable to do away with a rearwardly extending portion which provides spiking facilities to the rear tie, because in that case the tie in the rear of the joint will not be drawn along by the usual spiking because of the fact that the grip of the spike on 70 the foot of the rail is inadequate to keep the rail from creeping between the head of the spike and the tie. The result is, therefore, that the spacing between the two ties nearest the abutting ends of the rails is gradually increased by the rear tie lagging behind and the front tie being pushed ahead by the downwardly extending flange of the splice bars. 75

It is generally recognized among engineers that, for high speed tracks carrying heavy 80 loads, the tie spacing at the joint must be considerably closer than is necessary elsewhere along the unbroken rail. While this practice has been the outgrowth of deficiencies in the rail joints in most general use, 85 which have made it necessary to place the ties more closely together in order to give greater supporting resistance to the deflection of the abutting ends of the rails, the practice has, however, become so well established as to be recognized as a fixed custom 90 and must be recognized in the design of a practically commercial joint.

My construction and arrangement is independent of any particular form of the depending portion or flange, or of the body of the bar. In the accompanying drawings, I have illustrated a number of different forms of splice bars embodying my invention, and it may also be embodied in numerous other 95 forms.

In the several figures of the drawing, the numerals 2 and 3 designate the rails, 4 the tie in advance of the joint, and 5 the tie in the rear of the joint. 6 designates the splice bars which, in all the forms shown, have a longer arm or extension to the rear of the joint than in the opposite direction, this long arm or extension being arranged to extend back over the base of the rail above the tie 5 100 and being provided with means, preferably spike slots 7 for the reception of the usual

spikes 8, whereby it may be anchored to the tie 5.

In the form shown in Fig. 1, the splice bar is formed with the depending flange or projection 9 having a straight front edge arranged to bear against the rear of the front tie 4. In Fig. 2 the depending projection 10 of the splice bar is shown as curved at both its front and rear edges, the former being adapted to engage the tie 4. In these two figures, the flanges 9 and 10 are freely depending. The depending flanges or portions of the bars at opposite sides of the rails may, however, be connected together. Fig. 3 shows them so connected by bolt 11, while Fig. 4 shows them connected by a clamp 12.

In the construction shown in Fig. 5, the ends of the splice bar are cut or sheared obliquely, as shown at 13, the oblique cut at 20 the forward end extending down to the bottom of the depending projection.

In the construction shown in Figs. 6 and 7, the forward end of the bar is in the form of a compound curve 14, the curves in the two figures being shown as of reverse form. Fig. 7 also shows the bar as having a shorter front arm or extension than in Fig. 6, with a greater length in the depending projection 15.

In Fig. 8 the splice bar is shown as of that form in which the portion extending below the lower face of the base of the rail is turned inwardly underneath the base to bear against the same, instead of depending freely between the ties.

Fig. 9 shows a joint similar to that shown in Fig. 8, with the exception that only one of the splice bars, (the one on the farther side looking at the figure), extends underneath the base of the rail. Although two or more bars of the same or varying conformations may be necessary in all cases to the formation of the complete rail joint, it will be obvious from the foregoing that only one of the bars need involve the principle of my invention, since the rear portion of this bar, extending backward over the rear tie, may be anchored securely to that tie through the medium of one or more spikes engaging one or more spike slots in the rearwardly extending arm. Therefore, since the principle of my invention may be carried out at one side only of the rails, additional bars may be added at this side, and one or more bars used at the opposite side, such auxiliary bars being of any desired form, so long as at least one of the bars in the joint embodies the essential features above described. Thus, in the joint shown in Fig. 9, the splice bar 16 may be an ordinary fish plate or angle bar, or a channel bar, used either singly or in conjunction with a bar or block of steel, iron, wood, insulating material, or other substance.

Fig. 10 illustrates another form of bar having ribs or lugs 17, which extend laterally to a slight or considerable extent from the base of

the rail, and over one or more ties. These ribs or flanges may be joined to the depending portion 18 by means of the gussets 19.

In Fig. 11 a joint is shown in which two bars of similar formation are placed in reverse positions at opposite sides of the rails, so that the longer portion of one bar will extend forwardly past the front end of the other bar, and over the tie in advance of the abutting ends of the rails. A similar joint is shown in Fig. 12, but with the bars of somewhat different form and having oblique ends. This arrangement, particularly as illustrated in this figure, will be found very advantageous in practice, on account of the increased top bearing of the forward portion of the bar underneath the head of the rail.

As before stated, various other forms of bars may be used in carrying out my invention, the particular shape and cross-section thereof being immaterial.

In addition to the advantages above described, a further important advantage from the manufacturers' standpoint, results from the fact that the bars are greatly cheapened by reason of the saving of superfluous metal at the forward ends. Common practice in the drilling and designing of rail joint bars has heretofore caused both ends of the bar to be of substantially the same length, or symmetrical, with reference to the abutting ends of the rails. By shortening the forward arms of the bars in the manner described, it is evident that a large saving in material is effected. In those types of bars in which the end portions of the downwardly extended flanges must be sheared away to make room for the ties, a further material saving is effected. This will be more particularly apparent from inspection of Figs. 1, 3, 5, 11 and 12, in which only the rear portion of the depending flange need be sheared away to make room for the tie, which effects a saving of about one-half in the shearing cost over present methods. These advantages are of especial importance because of the fact that in recent years the wheel loads of engines and cars have increased so rapidly that the necessity for the use of rail joints having a large factor of vertical stiffness is largely recognized as essential to the proper maintenance of safe and economical track; but the use of the large amount of additional metal required, and the more difficult manipulation in the finishing of the bars, has heretofore added greatly to the cost of a complete joint in which this larger factor of stiffness is present.

What I claim is:

1. A splice bar having a portion to extend below the base of the rail, and designed to fit on one side of two adjoining rails and having each half of its length unsymmetrical with reference to a vertical plane equidistant from the ends of the bar and at right angles to the bar; substantially as described.

2. A splice bar having a portion to extend below the base of the rail, and designed to fit on one side of two adjoining rails and having its end portions unsymmetrical with reference to a vertical plane through a point opposite the adjoining ends of the rails and at right angles to the bar; substantially as described.

3. A rail joint having two splice bars of similar form, applied to opposite sides of the rail in a reverse position, the two arms or end portions of each bar being of unequal lengths; substantially as described.

4. A rail joint having each of its two splice bars unsymmetrical with reference to a vertical plane through a point opposite the meeting ends of the rails and applied to the

opposite sides of the rails with their longer ends extending in opposite directions; substantially as described.

26

5. A rail joint having each of its two splice bars similar in form and unsymmetrical with reference to a vertical plane through a point opposite the meeting ends of the rails, and applied to the opposite sides of the rails so that the similar ends extend in opposite directions; substantially as described.

25

In testimony whereof, I have hereunto set my hand.

WILLIAM P. THOMSON.
